UNITED STATES PATENT OFFICE.

WALTER L. DIXON, OF BOSTON, MASSACHUSETTS, ASSIGNOR TO REECE FOLDING MACHINE COMPANY, OF BOSTON, MASSACHUSETTS, A CORPORATION OF MAINE.

FOLDING METHOD AND PRODUCT.

Original application filed April 3, 1924, Serial No. 703,951. Divided and this application filed June 9, 1924. Serial No. 718,834.

This invention involves a novel folding method and product, the method referring to the infolding of the edges of cloth or other blanks, for example the cloth blanks used in the manufacture of collars and cuffs, and the product consisting of the folded blank or completed collar or other article embodying the novel fold of this invention.

10 The general object is to afford an improved method and product of general and specific utility. A special object is to improve the art of folding cloth blanks for collars, cuffs and various analogous articles. 15 A particular object is to enable the efficient and satisfactory manufacture of folded articles wherein one or more of the corners to be folded presents a fairly sharp angle, or an acute angle, substantially less than 90°. 20 Such corners have presented problems on account of the difficulty in producing a satisfactory fold and accommodating the excess of marginal material within the small compass of the acute angle, without causing excessive thickness or producing bunching of material which would often render a product uncommercial or at least require additional labor and cost in trimming the excess material. Other and further objects of 25 the present invention will be explained in the hereinafter description of an embodiment thereof, or will be apparent to those skilled in the art.

To the attainment of the objects and advantages referred to the present invention consists in the novel method of operation or manufacture, and the novel infold or product, as well as the novel features of combination, arrangement, construction, mode of action and detail, herein illustrated or described.

This application is a division of an application filed April 3, 1924, Serial Number 703,951 for folding machine, method and product, patented July 6, 1926, No. 1,591,613, which may be referred to for many details, including the preferred machine or apparatus for carrying out the method of this invention and manufacturing the product hereof.

In the accompanying drawings Fig. 1 shows a portion of a blank of cloth or other sheet material, having an acute corner to be folded, between 45 and 90°; the dotted lines indicating the lines of the eventual folds,

usually defined by a plate or templet during the folding, as more fully explained in the application of which this is a division. Figs. 2 to 4 illustrate intermediate steps in the process of folding the blank. Fig. 5 indicates the completely folded blank, being an article complete in this sense, and in condition to be incorporated in a collar or other commercial article. Fig. 6 shows a sharp pointed collar adapted to be manufactured from blanks produced in accordance with the other figures.

The collar 20 shown in Fig. 6 is a turnover collar having the inside portion or collar band 21 and the outside portion or collar top 22, the latter having an acute angled point 23, the angle being substantially less than 90° and greater than 45°. The dotted lines indicate the arrangement of the interior folds or flaps as will be explained from the other figures. It will be understood that in constructing a collar top two folded blanks are assembled and stitched together with their infolded margins at the interior. In the case illustrated each of the two blanks 24 may embody the present invention, and each blank may consist of one or more plies of fabric. The two blanks assembled to form a collar top may have the folds or flaps oppositely formed so that each may be tucked in under the other, forming what is known as a lock corner, or this feature may be omitted.

In order to describe the steps in forming the folds, according to this invention, I start with the original fabric blank 24, the pertinent portion of which is shown in Fig. 1. For convenience this is shown as a single ply blank. The dotted lines, 25 along the side and 26 along the end, indicate where the folds are to be formed, and correspond to the die and to the final shape of the folded blank and collar. The intersection of these is the acute angle corner 23, already mentioned. Outside of the line 25 is the side margin 27 of the blank and at the end is shown the margin 28, while at the corner is the rhomboidal margin portion 29.

While the blank, so described, is defined by a die or templet the margins are manipulated in a special way to produce an orderly formation of the material into definite flaps or folds which are laid over and positioned in such a way as to minimize the difficulties before referred to. In general the

method comprises the formation of an intermediate or upstanding flap of the excess material and laying this down flatly on top of one of the two lineal folds and then laying 5 the other lineal fold or margin down flatly upon it. The progress is shown in the successive drawings, Figs. 1 to 6. In Fig. 2 the side margin 27 is shown bent up from the plane of the blank. This and the suc- 10 ceeding steps may be performed by mechanism such as shown in the prior application. In Fig. 2, while the side margin 27 is being folded along the line 25, the corner margin 29 appears in a warped condition, the initial 15 stage in the formation of the intermediate flap or fold.

The completion of the infolding action along the side is indicated in Fig. 3. The margin 27 has been laid flatly down into its 20 final position. The corner fabric portion 29 however has been formed into an upstanding loop, flap or fold 30. While this may be effected in different ways, the prior application shows mechanism by which a side in- 25 folding plate, with a notched formation near the apex 23, is adapted to produce the intermediate loop or flap 30.

The next stage, shown in Fig. 4, indicates the laying down flatly upon the infold 27 30 of the loop or flap 30. The end margin 28 is yet unfolded with the exception that a portion 31 thereof, adjacent the corner of the blank, has been folded upon itself, as indicated in Fig. 4, during the formation of 35 the flap 30. The intermediate flap or fold 30 is to be of such dimension that when laid down as in Fig. 4 it will lie wholly within the angle of the completed blank, and not project beyond the final outline.

40 The next operation is indicated by the final condition, shown in Fig. 5, in which the end margin 28 has been folded over, inwardly and down upon the body of the blank and the flap 30. While the folded blank shown 5 in Fig. 5 is the preferred embodiment it may be varied somewhat within the scope of this invention. The specific steps and procedure may be varied. The product or infold is seen to be compact and free from 50 bunching, wrinkling or other results which would tend to spoil the quality or saleability of the completed collar.

The completed collar, shown in Fig. 6, 55 may comprise the collar top 22 consisting merely of two folded blanks as in Fig. 5 assembled and stitched together. If a lock corner is desired, it is only necessary to reverse the steps so that the end fold 28 is turned in first and the side fold 27 is turned 60 in last. A blank so folded will interlock with a blank as in Fig. 5.

When the acute angle of the folded blank 65 is to be less than 60° it is obvious that the described process must be modified to accommodate the entire fabric within the

angle; and the principles of the present invention may be employed in different ways, for example by manipulating the infolders to produce two, instead of one, of the upstanding flaps or folds 30; or in the case 70 of a single flap this may be folded back upon itself to prevent any portion of it standing out beyond the outline of the product.

The apparatus for carrying out the de- 75 scribed product may be of any desired type or construction, but preferably, as disclosed in said prior application, it comprises a blank supporting bed or pad, with a die or templet adapted to rest upon the blank 80 and define the shape thereof, and movable infolders adapted to move in from the sides in a manner to carry out the present process and produce the product hereof.

It will be noticed that the infolded blank 85 of this invention is one in which the infolded portions at a pointed corner or apex are arranged in orderly manner in flat portions or folds, and that there are an odd 90 number of layers greater than three, namely five, but increased to seven if two intermediate flaps should be formed or one flap formed and folded back upon itself. Stated another way, the infolded blank comprises the inturned lineal margins which meet at 95 the corner and one or more flaps or loops of material composed of the excess marginal material at the blank corner. The method involves the folding in of the two lineal margins, and arranging and laying down 100 flatly in the form of flaps the excess corner material, preferably in advance of completing the lineal folds. In any case there are five or more flat layers of infolded fabric superimposed within the angle of the corner. The lineal folds and flaps are produced by three operations, or perhaps more. Specifically one lineal margin is folded in and down and the corner material is formed into 105 a flap and laid upon the first fold and then the second lineal margin is folded in upon that. All the operations are effected in immediate sequence, in the same machine, and without shifting of die or blank, an important factor in attaining commercial results. 115

The method hereof may be described as producing an infolded blank having an acute angled corner 23, formed by the fold lines 120 25 and 26 of two infolded margins, comprising infolding the first of the two lineal margins adjacent such corner, namely margin 27, and forming the excess corner material 29 into the doubled flap 30 which may be described as having its base hinged directly to the first lineal margin 27 already infolded and to the second lineal margin 28 not yet infolded, with the hinge line between the doubled flap and the first infolded margin 27 lying between the fold lines 25 and 26 of the margins, as seen in Fig. 3, and then in- 125 130

folding the second lineal margin 28 in and down upon such flap and upon the first margin, giving the condition seen in Fig. 5; and the product or collar may be analogously 5 described as having the intermediate doubled flap with its base hinged as stated; it being understood that the location of the hinge line between the fold lines 25 and 26 admits of its coinciding with one of them so long 10 as it does not fall outside of the acute angle between them.

It will thus be seen that there has been described a folding method, and a folded blank or article, embodying the principles 15 and attaining the advantages of the present invention. Since many matters of arrangement, combination, structure, order of steps and detail may be variously modified without departing from the principles it is not 20 intended to limit the invention to such matters except in so far as set forth in the appended claims.

What is claimed is:

1. The method of producing an infolded 25 blank having an acute angled corner, formed by the fold lines of two infolded margins, comprising infolding the first of the two

lineal margins adjacent such corner and forming the excess corner material into a doubled flap with its base hinged directly 30 to the infolded first margin and the unfolded second margin, with the hinge line between the doubled flap and the infolded margin lying between the fold lines of the margins, and then infolding the second margin in 35 and down upon such flap and the first margin.

2. A collar or analogous article having an acute angled corner and comprising an infolded blank with similar acute angled corner, formed by the fold lines of two infolded 40 margins, and consisting of its body with an underlying infolded first lineal margin, adjacent such corner, and overlying that a doubled flap with its base hinged directly 45 to the infolded first margin along a hinge line lying between the fold lines of the margins and directly upon the blank body, and above that the infolded second lineal margin similarly hinged to said flap. 50

In testimony whereof, I have affixed my signature hereto.

WALTER L. DIXON.
